(57) **CLAIM**

The ornamental design for a fluid container, as shown and described.

DESCRIPTION

FIG. 1 is an isometric view of a fluid container showing my new design;

FIG. 2 is a top isometric view of the fluid container, shown with the cap removed;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof showing my design.

1 Claim, 6 Drawing Sheets(56)
